UNITED STATES PATENT OFFICE.

EDWARD E. STROTHMAN, OF WEST SUPERIOR, WISCONSIN.

DESIGN FOR A PROPELLER.

SPECIFICATION forming part of Design No. 35,485, dated December 10, 1901.

Application filed September 28, 1901. Serial No. 76,959. Term of patent 14 years.

To all whom it may concern:

Be it known that I, EDWARD E. STROTHMAN, a citizen of the United States, residing at West Superior, in the county of Douglas and State of Wisconsin, have invented and produced a new and original Design for Propellers; and I do hereby declare the following to be a full, clear, and exact description of the same, reference being had to the accompanying drawings, forming a part thereof.

In the accompanying drawings, Figure 1 represents a view in side elevation of a propeller constructed in accordance with my design. Fig. 2 represents a transverse vertical central section through the same; and Fig. 3 represents a top plan view of the hub, showing a transverse section through one of the blades on line 3 of Fig. 1, the other blades being omitted.

The principal features of my design comprise a central hub and blades radiating therefrom and set upon angles of substantially thirty-eight degrees with relation to the longitudinal axis of the hub, each of the blades gradually increasing in width from its line of jointure with said hub for about one-fourth of the distance from the axial line of said hub to the outer end of said blade and from thence to the outer end being substantially of uniform width and having its forward face convex, said face tapering in both directions from a central vertical line to the outer edges, whereby both edges near the hub are comparatively sharp, the rear face of the blade being also convex, but of less convexity than the front, the central thickness of each of the blades being greatest near the hub and gradually decreasing outwardly to the end, the said blade curving or bending rearwardly from approximately one-fourth of its length to its outer end. Each of the blades has its outer end curved and formed with a flange or lip extending from the rear thereof for the entire width of the blade, the outer face of each of the flanges being curved or rounded, as shown, the flange being of the same width throughout its length, but slightly rounded at its outer corners.

In the drawings, 1 represents a cylindrical barrel-shaped hub formed with a longitudinal bore 2, in the surface of which is provided a groove 3 for the reception of a key or spline.

4 4 represent propeller-blades which radiate from said hub and are set at angles of substantially thirty-eight degrees, more or less, 55 to the longitudinal axis thereof. Each of the blades gradually increases in width from its line of merger with said hub to an imaginary transverse line about one-fourth of the distance from the axial line of said hub to the 60 outer end of said blade, and from said imaginary line to the said outer end is of substantially uniform width and has its forward face convex, said forward face tapering from the thickest portion on the central longitudinal line in both directions to the outer edges, whereby both edges near the hub are comparatively sharp, the rear face of the blade being also convex, but of less convexity than the front. The greatest central 70 thickness of each of said blades is at the point of jointure with the hub and tapers outwardly to the outer end, the said blade gradually curving or bending rearwardly from approximately one-fourth of its length to its 75 outer end. Each of blades 4 is curved at its outer end and provided with a flange or a lip, as 5, extending transversely of the same for the full width of said blade, each of said flanges projecting rearwardly from its respective blade and being provided with a curved outer face and preserving the same width and thickness throughout its length, but slightly curved at its outer corners. The rear face of the body of each blade has a comparatively 85 flat transverse axis and a bent longitudinal axis, and the heel of each blade merging spirally with said hub, extending one-half way around the hub and from a point at or near one end of said hub to a point at or near the 90 other end of the same, gives strength to a comparatively light hub.

Having thus described my design, what I claim as new, and desire to secure by Letters Patent, is—

The design for a propeller substantially as herein shown and described.

In testimony whereof I hereunto affix my signature in presence of two witnesses.

EDWARD E. STROTHMAN.
